UNITED STATES PATENT OFFICE.

CHARLES GREIF RAIBLE, OF LAKWOOD, OHIO, ASSIGNOR TO THE FANNER MANUFACTURING COMPANY, OF CLEVELAND, OHIO, A CORPORATION OF OHIO.

CHAPLET.

Application filed August 23, 1926. Serial No. 130,837.

The present invention relates to chaplets used in connection with molding operations for positioning and supporting a core in place in the cavity in the mold.

Reference should be had to the accompanying drawings forming a part of this specification, in which

Fig. 1 is an elevation of a chaplet;

Fig. 2 is also an elevation taken in the position at right angles to that shown in Fig. 1;

Fig. 3 is a top plan view of chaplet with portion shown in dotted line;

Fig. 4 is a section on the line 4—4 of Fig. 2;

Fig. 5 is a section on the line 5—5 of Fig. 2, and

Figs. 6, 7 and 8 are modified forms of the chaplet.

As is well known, chaplets are used to position and support a core in the cavity in the mold and when iron is introduced into the mold the iron flows around the body of the chaplet incorporating the chaplet as a part of the body of the iron, so that the chaplet is 25 "burnt in" to the body of the iron.

When the casting is removed from the mold, any protruding portions of the chaplet are removed by chipping the same or otherwise and it is frequently found that the chaplet has not become completely "burnt in" to the body of iron so that the chaplet is more or less surrounded by a small cavity in the body of the iron itself.

Under such circumstances, it is common practice to pean the chaplet so that it is spread slightly to fill up the cavity in the iron and to produce a smooth and finished surface for the casting.

The present invention is directed to a form 40 of chaplet which is incorporated into the body of metal forming the casting in such manner that if peaning is required, the chaplet itself will be so incorporated in the body of metal as to have a firm anchorage therein 45 permitting the peaning action without danger of driving the chaplet through the wall of the casting. In fact, when the chaplet is peaned a wedging action takes place which causes the metal of the chaplet to completely 50 fill in the cavity in the wall of the casting.

Referring to the drawings, 1 and 2 indicate the end members of the chaplet, while the

connecting portion is represented at 3. This connecting portion is formed with broad re-entrant grooves, such as indicated at 4 and 5, and in the forming of these grooves, which preferably is done by a swaging action, the opposite sides of the connecting portion 3 are slightly bulged outward at the center as indicated at 6 and 7.

When, therefore, this chaplet becomes incorporated in the metal of a casting, there will be metal occupying the grooves 4 and 5. There will also be metal surrounding the bulged portion of the connecting member 3. 65 This will give a firm anchorage for the chaplet in the metal of the casting.

Additionally, if peaning is required, the compression of the metal on the chaplet will tend to wedge it into any cavity or spaces that 70 may surround the chaplet, thereby giving the chaplet a firmer and more complete incorporation in the metal of the casting.

In Figs. 6, 7 and 8, a modified form of the chaplet is shown, comprising the end members 1^a and 2^a with a central connecting portion 3^a. The grooves 4^a and 5^a are provided as well as the bulged portions 6^a and 7^a. In addition the recesses are traversed by ribs 8 and 9, which give slightly more metal at what 80 would otherwise be the thin cross-section of the central member of the chaplet, thereby preventing the molten metal as it contacts with the chaplet from burning through the body of the chaplet.

All the advantages which have been heretofore described are maintained in the modified form of chaplet, with the additional provision of the ribs which prevent the metal burning through the body of the chaplet.

Having thus described my invention, I claim—

1. A chaplet comprising substantially flat end members, a connecting body portion, opposite parts of said body portion being formed with re-entrant grooves, said body portion having longitudinal extending ribs at substantially the central portions of said re-entrant grooves, the said body portion also being bulged outwardly at points intermediate the said grooves.

2. A chaplet comprising substantially flat end members and a connecting body portion, said body portion being formed with oppo-

sitely disposed reentrant grooves and having longitudinally extending rib members formed in the body portion and substantially at the central portion of said grooves, the cross sectional area of the body portion being substantially uniform throughout its extent.

3. A chaplet comprising substantially end members and a connecting body portion, said

body portion having transversely extending reentrant grooves formed therein, and longitudinally extending rib members formed in the body portion and substantially at the central portion of said grooves. ¹⁰

In testimony whereof, I hereunto affix my signature.

CHARLES GREIF RAIBLE.
